TELEGRAPH-CODE TAPE PUNCH

Lester D. Walden, Los Angeles, Calif.

Application February 1, 1935, Serial No. 4,497

19 Claims. (Cl. 164—112)

This invention is a tape punching machine of the class used for the preparation of telegraphic code transmission tape.

An object of the invention is to provide a machine of this type which is capable of rapidly and practically punching holes of different length in the tape for spelling a code word and to effect spacing between code words along the tape.

A further object is to effect the automatic feed 10 of the tape by means under control of the punching means and provide means to effect the tape feed independently of the punch means for spacing code words punched in the tape.

An additional object is to provide punching 15 means including a single punch member operative to form either a short or small aperture representative of a "dot" in the code and also, selectively, to form a long or large aperture for the dash sign of the code. And in this connection an object is to provide for the utilization of 20 the same punch member to control tape feeding means.

More specifically, an object is to provide means to cut a tongue of desired length in the tape and to 25 fold the tongue back against one face of the tape to define a hole ending at the fold of the tape tongue and beginning at the cut end of the tongue.

An important object is to provide for conservation 30 of tape stock and yet obtain code perforations of such length and of such letter and word spacing as not to in any manner reduce the impulse efficiency of the sending apparatus in or on which the tape may be employed for code purposes.

The invention consists in certain advancements 35 in this art as set forth in the ensuing disclosure and having, with the above, additional objects and advantages as hereinafter developed, and whose construction, combination and details of 40 means, and the manner of operation will be made manifest in the description of the herewith illustrative embodiment; it being understood that modifications, variations and adaptations may be resorted to within the scope, spirit and principle 45 of the invention as it is more directly claimed hereinbelow. It is understood that the functional use of the apparatus of this disclosure in any other art than that herein set forth is deemed to be within the adaptation of the invention.

50 Figure 1 is a side elevation of the machine, with the punch in the position of rest and free of the tape, and

Figure 2 is a plan view thereof.

55 Figure 3 is a perspective of the detached punch-throat tape bed.

Figure 4 is a detail sectional view showing the step of folding the punched tape tongue.

Figure 5 is a plan of a piece of the punched tape showing the unit value of the dot, the dash and the space blank between words.

The main frame structure includes spaced side plates 2 and 3 having at one end bearings 4 with a spindle 5 for the ready application of a roll of blank, code tape T in which are to be punched groups of holes permitting electric contact in 10 telegraphic code senders (not here concerned). Figure 5 illustrates the punched tape with the form of punched holes produced in the machine here shown.

To send a dash signal this tape is punched to 15 form a long aperture D, and to send a dot signal it is punched to form a short aperture O. Groups of such holes forming a code word are spaced by blank tape shown at the zone S. The machine includes means, later described, to advance the 20 tape a step equal to the space zone S, between word groups of holes D—O, and to advance the tape a step for a dash hole which step is equal in length to the length of the space zone S. Such zone is here considered as the unit measure of 25 tape feed. The tape punching means includes a device, later described, which will cut a tongue G, Fig. 4, which has a length of about three-quarters of a step unit, thus leaving a tie or web W at the end of the dash hole D, Fig. 5. Now, 30 for convenience, the dot zone Z is about half as long as the zones for a dash D or space S, individually; or, in other words is half a step unit. The dot hole O is about half the length of its zone Z.

35 As a result of this measure of dot and dash zones the long tongue cut to make a dash hole will, in operation of the machine, be folded back under the advancing tape (note the left end of the tape, Fig. 1) and cover the leading end of the next hole punched in the tape. In the method here disclosed of preparing the code tape this covering and undesired part of the tongue will be cut off by the punch means to leave the affected hole entirely clear for signal transmission. Thus is produced a minimum dot hole and tie web W and a sufficiently long dash hole to characterize the code sign.

The tape T passes from the roll to guide rollers 6—7 journaled between the frame plates and 50 thence to the top channel 8^a of a die or bed plate 8 suitably secured between the frame plates 2—3. This bed has a central, elongated die throat 8^a pointed at one end 8^b and square across at the other or root end 8^c.

55

Cooperative with the bed and closely matching its pointed end and parallel sides throat 8^a there is pivoted on a trunnion or shaft 9, across the channel of the bed 8, a segmental punch or cutter 10 beneath which the tape moves along the bed and over the die throat. In order to facilitate the clean cutting of the back-folded part of a tongue G, as above described, the leading end of the chordal edge 10^a of the cutter is provided with a forwardly extending incising nib 18^a, which, with the rim of the segmental punch 10, is of angular contour matching the pointed end of the die throat.

Means are provided to utilize the single punch 10 for lacerating the tape to form either long or short tongues and, as a corollary, the dash signal hole D or the dot signal hole O. As here depicted, the punch is provided with lateral lugs 11-12, above its pivot 9, respectively drawn back against manual keys 13-14 by a spring 15 which allows the punch to be downwardly motivated by either of its keys 13-14, selectively, by the operator of the machine.

The keys have a common axis of motion 16 and have respective pull-back springs 17-18 normally holding the levers against a back-stop 19. The length of key stroke determines the length of the tongue and hole made in the tape by punch action and to determine such stroke the keys move against differential stops, 20 for the "dot" key and 21 for the "dash" key (as designated in Fig. 2). Therefore when the dash lever or key 13 is depressed it presses on its lug 11 and drives the punch 10 down through the tape on the bed 8 and bends down the cut tongue G to a position in front of the breast 3^d at the point end of the die throat 8^a to make a long tongue. Operation of the dot key 14 brings it up against its stroke-stop 20 and effects a short cutting action of the punch to produce the dot signal hole and short tongue. As soon as operative pressure is removed from the depressed key, it and the punch are both instantly retracted by the relative springs (17-13 and 15).

Means are provided to automatically advance the tape following punch action a degree in accordance with the tape unit measure of a dot or a dash. While the feed means is of automatic character its feeding function is determined by the stroke of the punch member and, therefore, in the present disclosure the feed means is directly controlled by the punch.

The feed means includes a feed cylinder 22 journaled in the main frame in a position to receive the punched parts of the tape which is pressed to the cylinder by a pressure or creasing roller 23 journaled parallel to the cylinder and coactive with it to advance the tape and having the further utility of firmly creasing the fold of the tongue coming from the breast of the die bed, Fig. 4.

To the cylinder 22 is fixed a ratchet disc 24 whose teeth are engaged by a feeder pawl 25 suitably movably guided in the main frame parts and having a spring 26 constantly drawing the pawl tooth 25^a against the near face of the disc 24 for operative relation. The pawl stem projects upward to a position near an overhanging tapet arm 27 which is fixed to the punch 10 in any desired manner so that when the punch is swung down it will depress the pawl enough to pass one ratchet tooth if the dot key has been struck, or to pass two ratchet teeth if the dash key has been actuated by the operator. A stop latch 28 prevents a reverse turn of the ratchet disc 24

under pressure of the pawl tooth 25^a as it is forced down during punch action.

Upon completion of the punching step as soon as the operator releases the effective key 13 or 14 a main spring 29 attached to the feed pawl is then free to automatically pull up the pawl and to turn the feed cylinder, through the ratchet device, and feed the tape along the die bed an amount according to the number of ratchet teeth passed on the pick-up or down stroke of the pawl 25.

A two-tooth pick-up will advance the tape a full dash or space unit, as above defined, while a one-tooth pick-up will advance the tape only a half unit or dot zone length.

In code transmission a space or noticeable period of time follows each word group in the code and for this reason means are here provided to characterize this space on the tape after each full code signal, whether a single dot, or a single dash, or any combination thereof. This is accomplished by means working on the feed means independently of the punch means per se.

As here shown the space means includes a finger bar 30 across the key end of the machine and having side levers 31-32 which may hang on the axis 16 of the punch keys. Suitable connection as a pin and slot device 33 is provided between the lever 31 and the feed pawl 25 and when the space bar is depressed its full stroke the pawl is caused to pick up two ratchet teeth. On release of the space bar by the operator the main spring 29 instantly acts to pull up the feed pawl and effect a full unit turn of the cylinder 22 to correspondingly advance the tape. A suitable stop 34 limits the space bar stroke and thereby the feed pawl motion.

The spring 26 is given the dual function of drawing both the pawl 25 and the latch 28 to effective positions on the ratchet disc.

It is believed that the operation of the machine is obvious from the above detailed description of the parts and their actions.

What is claimed is:

1. A code tape punch having, in combination, a tape bed, having a punch that over which a tape passes, means to feed the tape in steps of predetermined length, and a punch member operative to punch apertures of different length in the tape passing over the said throat and separate key means for moving the punch in differential strokes.

2. A code tape punching machine, having in combination, a tape bed with a punch throat, a punch member complementary to the bed throat, and means for moving said punch in selective strokes of different length to punch different sizes of holes in the tape passing over the bed.

3. A code tape punching machine, having in combination, a tape bed with a punch throat, means to feed tape over the bed, a punch member for punching the tape on the bed; said member having means to actuate the feed means and key means to move the said member in strokes of different length.

4. A code tape punching machine, having in combination, a tape bed, a punch member cooperative with the bed to punch the tape thereon, feed means controlled by the said member to effect advance of the tape, and selective means to move the said member in punch steps of different length for making punch holes, in the tape, of different length.

5. A code tape punching machine, having in combination, a tape bed, a punch member co-

- operative therewith for tape punching, feed means to advance the tape, a feed control device connected to the said member and a feed control device independent of said member, and selective means to move the punch member in punching steps of different length. 5
6. A code tape punching machine, having in combination, a tape bed and means to progressively feed tape along the bed, and means selectively operative to actuate the feed means for advancing the tape in steps of different length; said means including a single punch member cooperative with the bed to make cuts in the tape of different length. 10
15. 7. A code tape punching machine, having in combination, a tape bed and means to feed tape along the bed, means selectively operative to actuate the feed means for advancing the tape in steps of different length and including a single punch member cooperative with the bed to make cuts in the tape of different length, and selective means independent of the punch means to actuate the feed means to advance the tape in steps of uniform length. 20
25. 8. A code tape punching machine including a tape bed and tape feeding means, and a punch cooperative with the bed to form a tongue in the tape and controlling the length of the tape feed steps of the feed means. 30
30. 9. A code tape punching machine including a tape bed and tape feeding means, a punch cooperative with the bed to form a tongue in the tape and controlling action of the feed means, and selective manual keys to motivate the punch in strokes of different length and thereby determine the length of the feed steps of the feed means. 35
40. 10. A code tape punching machine including a tape bed and tape feeding means, a punch cooperative with the bed to form tape tongues which are folded back by the bed as the tape advances to form clear punch holes, and means to motivate the punch and vary the length of the cut tongues and the punched holes incident thereto in the tape. 40
45. 11. A code tape punching machine including a tape bed and a punch cooperative therewith to punch tongues from the tape, feed means to advance the tape and cause the tongues to be folded back on the tape, and punch operating means to control and vary the length of the punched tongues by action on and of the punch; said operating means moving the punch in strokes of different length and the punch having an actuator for the feed means. 50
55. 12. A code tape punching machine including a tape bed, a punch cooperative with the bed to punch from the tape tongues of different length, and selective key levers limiting the movement of the punch in retracted position and operative to drive the punch on strokes of different tongue length. 5
13. A code tape punch of segmental form having a chordal cutting edge with a leading incising nib and being pivoted on its arc axis. 10
14. A code tape perforator including a pivoted punch member, and selective keys for actuating the punch for differential strokes to cut different length tape holes. 15
15. A code tape perforator including a pivoted punch member, selective keys for actuating the punch for differential cutting strokes, means to feed the tape after punch action, and a die bed cooperating with the punch and operative to fold the tape cutting back of the tape strip as it is advanced. 20
16. A tape bed, means to feed tape along the bed, a tape punch cooperative with the bed to cut tongues in the bed, keys to move the punch in cutting actions of different length and through the punch predetermine the feed action of the feed means, and an independent feed control for 25 the feed means. 30
17. A tape bed, means to feed tape along the bed, punch means to cut dot and dash code holes in the tape, dot and dash keys to operate the punch means, and means actuated differentially concurrently with key action on the punch means to fix the length of the tape feed by said feed means, and space key means for acting on the feed means to advance the tape to space code signals along the tape. 35
18. A tape bed, means to feed tape along the bed, punch means to cut dot and dash code holes in the tape by depressing tongues therefrom, dot and dash keys to operate the punch means, means to determine the key stroke and so fix the length 40 of the holes and through the punch the action of the feed means, and a space key for acting on the feed means to cause tape advance thereby for spacing code signals along the tape. 40
19. A tape bed and a punch cooperative to cut 45 and depress tongues along the tape to make code holes therein, keys for effecting action of the punch to make long or short tongue holes, means to advance the tape along the bed, the latter acting to fold back the depressed tape tongues, and 50 means to crease the bend of the folded tongue; said punch operative to cut off a part of the tongue when the same overlaps an area of the tape which is in cutting position at the punch. 55

CERTIFICATE OF CORRECTION.

Patent No. 1,998,946.

April 23, 1935.

LESTER D. WALDEN.

It is hereby certified that error appears in the printed specification of the above numbered patent requiring correction as follows: Page 2, second column, line 46, claim 1, for "that" read throat; and that the said Letters Patent should be read with this correction therein that the same may conform to the record of the case in the Patent Office.

Signed and sealed this 18th day of June, A. D. 1935.
